CLAIM

The ornamental design for storage container, as shown and described.

DESCRIPTION

FIG. 1 is a perspective view of the storage container with a four-drawer configuration;

FIG. 2 is a perspective view of a second embodiment of the storage container with a six-drawer configuration;

FIG. 3 is a top plan view of the storage containers of FIGS. 1 and 2;

FIG. 4 is a perspective view of a drawer, shown separately for completeness of illustration;

FIG. 5 is a top plan view of the drawer of FIG. 4;

FIG. 6 is a bottom plan view of the drawer of FIG. 4; and,

FIG. 7 is a side elevational view of the drawer of FIG. 4. The broken lines shown are for illustrative purposes only and form no part of the claimed design.
